UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

LINE-CASTING MACHINE.

1,014,725.

Specification of Letters Patent.

Patented Jan. 16, 1912.

Application filed February 4, 1909. Serial No. 476,001.

To all whom it may concern:

Be it known that I, JOHN R. ROGERS, of the borough of Brooklyn, county of Kings, and State of New York, have invented a new 5 and useful Improvement in Line-Casting Machines, of which the following is a specification.

My invention has reference to line casting machines, wherein circulating matrices representing the various characters and spaces, stored in a magazine, are released by finger-keys in the order in which their characters are to appear in print; the released matrices are assembled or composed in line, together 15 with expandible wedge spacers or justifiers between the words; the composed lines being thereafter transferred momentarily to the face of a mold, where they form in relief type characters on the edge of a type metal 20 slug or printing bar cast in the mold; the line being thereafter elevated from the mold to a distributing mechanism by which the matrices are returned to the magazine channels from which they were discharged, while 25 the spacers are also restored to their magazine or holder, as shown, for example, in Letters Patent of the United States #436,532. In this class of machines, as ordinarily constructed, it is possible to accidentally 30 reverse or turn a matrix side for side in the assembling mechanism, and to carry the matrix thus reversed in the line to the casting mechanism and thence forward in the machine. It is also possible in 35 these machines to reverse the wedge spacers, which should always be inserted with the longer wedge on the one side. This reversal of the matrices and spacers results not only in the production of a blank surface on the 40 slug, but also in certain complications of, or interferences with the mechanism, unnecessary to detail herein.

The aim of my invention is to prevent the casting of slugs with the errors therein 45 due to the reversal of the matrices or spacers, by compelling the operator to correct the composed line if it contains a reversed matrix or spacer, before the line can be carried forward to the casting mechanism.

To this end it consists in combining with 50 matrices and spacers which are non-symmetrical but alike in form, a stop located immediately beyond the point of composition and in advance of the casting mechanism, so that if an attempt is made to ad-

vance the composed line, it will be arrested by the engagement of the stop with any reversed matrix or spacer.

I prefer, as the most simple embodiment of my invention, to provide the upper 60 widened end of the matrices and the upper widened end of the spacers or justifiers with a notch in one edge, and to mount in the assembling elevator or the intermediate channel through which the composed line is 65 transferred, or both, a fixed stop bar which will readily enter the notches, and which will therefore permit the composed line to pass forward without interference, while on the other hand the stop will encounter and 70 arrest those matrices which are reversed.

In brief, the invention includes broadly the combination of non-symmetrical matrices and spacers with parts adapted to prevent them from passing forward in the 75 machine if they are turned so as to present the wrong edge in the casting position.

With the exception of the parts herein-after specifically described, the machine may be in all respects similar to that described 80 in the patent above referred to, or those sold on the market under the trade-mark "Linotype."

Referring to the drawings: Figure 1 is a perspective view of the assembling elevator 85 and the intermediate channel of the Mergenthaler machine with my invention incorporated therein. Fig. 2 is a perspective view of a portion of the intermediate channel on an enlarged scale. Fig. 3 is a similar view, 90 showing one matrix in the proper or normal position, and the other in the reversed position and arrested by the stop. Fig. 4 is a cross section on the line 4-4 of Fig. 1. Fig. 5 is a side view of one of the matrices specially notched in accordance with my invention. Fig. 6 is a side view of one of the spacers containing a special or safety notch. Fig. 7 is an edge view of the same. Fig. 8 is a view illustrating a modified or alternative construction, in which the matrices have on opposite sides ears of different lengths arranged to run in guides of different widths. Fig. 9 is a similar view, showing an alternative method whereby the routing of 95 the matrices is utilized, combined with a corresponding bar mounted in the side of the channel.

Referring to the drawings, I represent the assembling elevator, mounted to slide verti- 100 105 110

cally, and having in its upper end a horizontal groove or channel to which the matrices Y are delivered one at a time, and in which they are assembled and sustained side by side, together with the intermediate wedge spacers or justifiers Z in a common line.

M is the stationary "intermediate channel," so-called, through which the composed 10 matrix line is transferred by the customary fingers L and L¹ horizontally to the left in its course to the casting mechanism after the elevator I has been raised to the proper level.

15 So far as described, the parts are constructed and operated in the same manner as the parts indicated by corresponding letters in Patent #436,532. Each of the matrices is constructed as usual, with ears projecting 20 from opposite edges at the upper and lower ends, and with one or more characters or matrices, y, in one edge. As heretofore constructed, these matrices are symmetrical or of like form on opposite edges, and the machines are so constructed that matrices may 25 be introduced into the assembler with either edge to the front, when in fact they should all stand with the matrices proper at the rear edge, in order that these characters may 30 be properly presented to the mold with which they coöperate.

In carrying my invention into effect, I make the matrices non-symmetrical; in 35 other words, of such form that when one is reversed in relation to the next their edges will not register or aline at all points. The preferred form is that shown in Fig. 5, etc., in which one of the upper ears of the matrix is provided with a special notch, y².

40 The spacers or justifiers Z, shown in Figs. 6 and 7, consist each of a short wedge, z, having supporting ears, and a longer wedge, z¹, connected with the first by a vertical sliding joint, as usual, so that the ears of the 45 short wedge will serve to suspend the device as a whole, and also to hold the short wedge from rising in the matrix line, while the longer wedge is free to be pushed upward through the line past its companion, in order to increase the thickness in the line and 50 thus elongate or justify the latter. I now provide the short wedge for the first time with a special notch or shoulder, z², in such position as to register with the special notch 55 in the matrices when they are assembled in a common line. On the rear wall of the intermediate channel, M, I provide a horizontal rib or stop, m, so located that if all the matrices and spacers stand in the proper 60 position in the line, the rib or stop m, will pass freely through the notches and permit the line to be transferred to the left, as usual, without hindrance. If, however, any matrix or any spacer is reversed in the line, it will 65 present a solid edge or an edge without a

notch, in such position that as the line is transferred to the left it will encounter the end of the stop m and be arrested thereby. In this manner the transfer of the line to the casting mechanism will be prevented until the offending matrix or spacer is removed from and reversed in the line in such manner as to present the proper edge toward the rear. It will be observed that the longer member z¹ of the justifier must slide upward 70 freely. It is for this reason that the notches y² and z² are located in the widened portion 75 of the matrices and spacers beyond the vertical face of the matrix, so that the matrices and spacers may be seated tightly against the face of the mold.

Instead of the construction above described, the matrices may be made as in Fig. 8, with an ear y⁴ on one side longer horizontally than the corresponding ear on the other side. When the matrices are of this form, the intermediate channel or any other guiding channel through which the line is delivered will be constructed as shown in Fig. 8, with slots or recesses to receive the ears, the slot on one side being deeper than that on the other, so that if the matrix be improperly reversed and the long ear presented opposite the shallow slot, it will be impossible for the ear to enter. Consequently, the advance of the matrices in the line behind it will be prevented.

Instead of providing the matrices with special notches, I may utilize for coöperation with the stop the so-called routing or recess y⁵ commonly formed in the edge of the matrix, as shown in Fig. 5, to receive the character or matrix proper, which is punched below this recess. If this routing is to be utilized, a stop bar or rib y⁷ is to be 100 located as shown in Fig. 9, to project into the routing. As the opposite edge of the matrix is without the routing, it is clear that the reversed matrix will be arrested by contact with the end of the rib. When the 105 routing is thus utilized and the rib properly located for coöperation therewith, the spacers will be notched in one edge to correspond, as indicated by dotted lines at z³, Figs. 6 and 7.

Having thus described my invention, what I claim is:

1. In a line casting machine, the combination of non-symmetrical matrices, double-wedge spacers having their shorter wedges 120 non-symmetrical, an assembler wherein the line is composed, and means for transferring the composed line to the casting position, together with a stop located in advance of the casting position, whereby the passage 125 thereto of the composed line is prevented in the event of its containing a reversed matrix or spacer.

2. In a line casting machine, matrices having notches y² in one side only, double- 130

wedge spacers having notches z^2 in the shorter wedges, the said notches y^2 and z^2 normally registering in the composed line, an assembler wherein the line is composed, 5 and means for conveying the composed line to the casting position, together with a stop m located in advance of the casting position to prevent the passage thereto of the composed line in the event of a spacer or 10 matrix being reversed.

3. In a line casting machine, the combination of a line of matrices and non-symmetri-

cal spacers, means for transferring the said line to the casting position, and a stop located in advance of the casting position to 15 arrest the transfer of reversed spacers.

In testimony whereof I hereunto set my hand this twentieth day of January, 1909, in the presence of two attesting witnesses.

JOHN R. ROGERS.
